UNITED STATES PATENT OFFICE

HARRY A. MITCHELL, OF NEW YORK, N. Y., ASSIGNOR TO TERMINAL PRODUCTS CO.
INC., OF NEW YORK, N. Y., A CORPORATION OF NEW YORK

DESIGN FOR AN ELECTRIC WATER HEATER

Application filed November 13, 1931. Serial No. 41,720. Term of patent 7 years.

To all whom it may concern:

Be it known that I, HARRY A. MITCHELL, a citizen of the United States, residing at New York, in the county of New York and State of New York, have invented a new and original and ornamental Design for Electric Water Heaters, of which the following is a specification, reference being had to the accompanying drawing, forming part thereof.

The figure is a side elevational view of an electric water heater showing my new design. The unseen opposite side looks the same as the side shown.

I claim:—

The ornamental design for an electric water heater substantially as shown and described.
